UNITED STATES PATENT OFFICE.

ERNST BELING, OF VIENNA, AUSTRIA-HUNGARY.

SAFETY DEVICE FOR MUFFLES, CUPOLAS, AND OTHER FURNACES.

1,121,969.

Specification of Letters Patent. Patented Dec. 22, 1914.

Application filed April 6, 1914. Serial No. 329,774.

To all whom it may concern:

Be it known that I, ERNST BELING, engineer, subject of the Emperor of Austria-Hungary, residing at Vienna, Austria-Hungary, have invented certain new and useful Improvements in Safety Devices for Muffles, Cupolas, and other Furnaces, of which the following is a specification.

The object of the present invention is a safety device for furnaces, muffles, or cupolas, of such construction that when the blast in the air duct or pipe is cut off, a valve, disk or the like opens, whereby the interior of the muffle is connected to the atmosphere so that the gases formed when turning the blast on again are rendered unexplosive.

The present invention consists of an adjustable valve which automatically opens when the blast is cut off, and only automatically closes when the blast has reached a given pressure. When the blast is turned on again and as long as the valve remains open, the blast blows the explosive mixture of gases into the atmosphere. To accomplish this it is advantageous to fix a disk-valve in the blast pipe, of which the spring is so adjusted that it keeps the valve open till the blast on being turned on reaches a given pressure.

The invention will be fully described with reference to the accompanying drawings.

Figure 1, enlarged details of valve. Fig. 2 shows the lower part of a cupola with a safety valve connected to the blast-pipe according to the present invention.

The safety device consists of a cast-iron cylinder *a* with a connection *i* and an upper perforated dome *b* and lower perforated dome *c*. The cylinder in its upper part is provided with the safety valve *d* and in its lower part with the air inlet valve *e*. The cupola valve is connected to the air duct *f* of the cupola *g* by means of the connection *i* to the air duct *h*. The inlet valve *e* is kept open by means of a spring *k* when the blast is off and automatically closes when the pressure in the blast pipe has reached a given pressure on turning on the blast. The spring *k* is adjustable so that it can be set to any desired pressure. The purpose of the air inlet valve is in the first place to prevent cupola explosions, so very frequent in practice. These explosions are caused by having the blast stopped during the working for some cause or other, when the carbon-dioxide is reduced to carbon-monoxid, flowing into the ducts. On turning on the blast

again oxygen is mixed with the carbon monoxid with the result that the mixture of gases fires and explodes. The danger of such explosion is prevented from the start by the use of the cupola valve, since as soon as the blast is turned off, that is, as soon as the pressure in the blast pipe has reached its minimum the valve disk *e* is lifted by the spring *k* and fresh air enters through the perforations in the dome *c*, and through the lower valve opening. The fresh supply of air serves the purpose of creating a natural draft, thus preventing the collecting of carbon-monoxid. The air-valve *e* is so constructed that on turning on the blast it blows first into the atmosphere, thus completely clearing the air ducts of any gases. Only after completely clearing the gases and on reaching a certain pressure does the air valve close automatically when the blast is then led into the cupola or muffle. Thereby all residual gases remaining in the air ducts are rendered unexplosive. It is only after exceeding the minimum pressure that the air inlet valve *e* closes automatically.

The safety valve *d* is for the purpose of affording an escape of any excess of pressure caused by the clogging up or clinkering of the perforations, thus protecting the blast and its gear. Furthermore, on the top of the safety valve *d* is a contact device, for ringing an alarm on exceeding the normal pressure.

The contact device consists as is shown in Fig. 1 of a lever or arm *l* which is fixed to the cap *m* of the dome *b*. Thus on the valve *d* opening the arm or lever is moved by the valve spindle *n* causing the electric contacts *o* and *p* to meet simultaneously closing the circuit.

Having now particularly described and ascertained the nature of my said invention and in what manner the same is to be performed, I declare that what I claim is:

1. A safety device for furnaces, comprising a casing adapted to communicate with atmosphere and having a valve seat therein, a valve movable in a rectilinear path in said casing and tending to seat upon prevalence of a predetermined pressure within said casing, and cushion means to resist the seating tendency of the valve.

2. A safety device for the purpose specified, embodying a casing comprising two valves, valve seats adjacent each of the end portions of said casing, a valve operatively

related to each seat, one of said valves being adapted to be unseated by excess pressure within the casing, and means whereby the other valve is held from its seat until a predetermined pressure prevails within said casing.

3. A safety device for the purpose specified; embodying a casing having a portion thereof perforated, a valve within said casing interposed between the perforated and intact parts of the casing, and adjustable spring means for holding said valve from its seat until a predetermined pressure prevails within the intact part of said casing.
- 10 4. A safety device for the purpose specified, embodying a casing having an intermediate intact portion and oppositely dis-

posed perforated end portions, a valve seat adjacent each of said end portions, a valve operatively related to each seat, one of said valves being adapted to be unseated by excess pressure within the intact portion of said casing, and means whereby the other valve is held from its seat until a predetermined pressure prevails within said intact portion.

In testimony whereof I have hereunto set my hand in presence of two subscribing witnesses.

ERNST BELING.
